ARTICLE HANDLING DEVICE

William E. Bauscher, Towson, Md., assignor to
 Western Electric Company, Incorporated, New
 York, N. Y., a corporation of New York

Application August 29, 1942, Serial No. 456,717

1 Claim. (Cl. 57—1)

This invention relates to article handling devices, and more particularly to fixtures for removing servings or the like from cords.

It is frequently desirable to remove the servings and/or fillers from a cord or from a portion thereof. Heretofore in performing this operation an operator grasped one end of a serving or filler and revolved it about the cord, a slow and tiresome procedure.

Objects of this invention are to provide devices for handling articles, and more particularly to provide a fixture for removing servings or the like from cords.

A device embodying the invention comprises an elongated hollow member for supporting therein an article around which is wound a stranded material, said hollow member having a slot formed therein through which the stranded material may be pulled to remove it from the article.

Other features and advantages of the invention will become apparent from the following detailed description of one embodiment thereof when read in conjunction with the accompanying drawing, in which

Fig. 1 is a front elevation of the article handling device attached to a work bench, and

Fig. 2 is an enlarged fragmentary cross section thereof taken on line 2—2 of Fig. 1.

In the particular embodiment of the invention disclosed in the accompanying drawing, a hollow cylindrical tube 10 is affixed to a work bench 11 by means of a number of metal straps 12—12. One end 13 of the tube 10 has a slit 14 formed therein, the open end of which is widened as at 15 to provide a bell shaped entrance.

This embodiment of the invention may be used to perform certain operations upon a cord 16, which may include a plurality of conductors 17—17 and fillers 19—19 held together by a serving 18 wound spirally around the conductors and fillers. It may be desirable to free the ends of the conductors 17—17 to permit tips to be applied thereon and, in performing this operation, an operator inserts the cord 16 through the unslit end of the tube 10 and pushes it through the tube until the end of the cord emerges from the slit end 13. The operator then grasps the serving 18 and pulls it back through the widened portion 15 into the slit 14. The tube 10 is of such a diameter as to permit the cord 16 to rotate

freely therein, and by pulling the serving 18 outwardly through the slit 14, the operator removes the serving 18 from the cord 16 while the cord rotates within the tube. Due to the spiral winding of the serving 18, the cord 16 advances toward the end 13 of the tube 10 as the serving is removed therefrom. Thus, the operator may easily determine when he has removed the desired amount of serving 18 from the cord 16.

When the desired length of cord 16 has been freed from the serving 18, the operator may break off the serving, remove the end of the fillers 19—19 from among the conductors, and prepare the ends of the conductors 17—17 for the application of tips thereto.

It is obvious that this device may be used to withdraw strands used as fillers in cords in a manner similar to that described for the removal of servings from cords and that it also

20 may be used to remove servings and fillers from entire lengths of cords as well as from limited portions thereof.

The advantages of the present invention lie in its simplicity and economy. The removal of 25 serving and fillers from cords, which heretofore required considerable time and expenditure of much energy by the operator, may be almost effortlessly accomplished in a matter of seconds with the use of the hereinabove described device.

30 Numerous changes may be made in the particular embodiment of the invention hereinabove described without departing from the spirit of the invention. The invention is not limited to the removal of serving or fillers from cords, but 35 is applicable whenever it is desirable to unwind a stranded material from an article.

What is claimed is:

A fixture for removing servings or the like from cords and cables, which comprises a stationary, elongated, metal tube having an elongated slot extending longitudinally from one end of the tube towards the other end thereof a distance sufficient to permit a serving or the like to be inserted therein from the open end thereof 40 and to be withdrawn through the slot from a cord or cable projecting longitudinally through the tube while the cord or cable rotates in and advances through the tube, and means for supporting the tube in operative position upon a bench or the like.

WILLIAM E. BAUSCHER.
